UNITED STATES PATENT OFFICE.

SEVERIN HALVORSEN, OF CHICAGO, ILLINOIS, ASSIGNOR TO THE NEWSPAPER STUFFING MACHINE COMPANY, OF SEATTLE, WASHINGTON, A CORPORATION OF WASHINGTON.

FEEDING DEVICE.

Original application filed May 20, 1922, Serial No. 562,462. Divided and this application filed October 25, 1926. Serial No. 143,852.

My invention relates to feeding devices and is herein shown and described in conjunction with a newspaper stuffing machine, such as shown and described in my copending 5 application, Serial No. 562,462, filed May 20, 1922, of which the subject matter of this application is a division.

The invention has among its various objects the provision of a device capable of 10 engaging and causing sheets or newspaper sections to be successively fed from a stack of sheets or sections.

It is an object to provide a structure which 15 will impart motion to the sheet to be extracted which motion will cause the sheet to be moved in one direction and removed from an abutment or support and then moved in the opposite direction to cause the sheet to be fed from the stack to other portions of the 20 machine.

It is a further object to provide a support 25 for the stack of sheets and to construct the support so that the means for feeding the sheets may be readily associated therewith.

In addition to the above it is an object to 30 provide a construction which permits the parts of the feeder to be readily separated should this be found necessary for the purpose of making repairs or adjustments.

In addition it is an object to provide an 35 arrangement which is simple and may be cheaply manufactured.

The invention will be explained in detail 40 and more readily understood when read in connection with the accompanying drawings which illustrate one embodiment of which the invention is susceptible, it being obvious that changes and modifications may be resorted to without departing from the spirit 45 of the appended claims forming a part hereof.

In the accompanying drawings Fig. 1 is a 50 front elevation of a newspaper stuffing machine having the invention applied thereto;

Fig. 2 is a view of an end of the structure 55 shown in Fig. 1;

Fig. 3 is a plan view of the structure shown 60 in Fig. 2;

Fig. 4 is a section taken on line 4—4 of 65 Fig. 3;

Fig. 5 is a longitudinal sectional view 70 through the feeding device;

Fig. 6 is a view similar to Fig. 5 showing 75 certain parts in a different position;

Fig. 7 is a section taken on line 7—7 of 55 Fig. 6;

Fig. 8 is a perspective view of one of the 80 elements shown in Figs. 5 and 6;

Figs. 9 and 10 are respectively front and 85 side elevations of a means for feeding the paper sections to the feeding device shown in Figs. 5 and 6; and

Fig. 11 is a front elevation of a portion of 90 the structure shown in Fig. 4.

The invention is herein shown and de- 95 scribed in conjunction with a machine for feeding newspaper sections and causing one section to be inserted within another and delivered as a unit from one end of the machine.

The various devices for causing the several 100 sections to be inserted are designated by the characters A, B, C, D, and E, each of which contains a pile of the various sections which are delivered to a delivery mechanism F. The structures of the various devices A to E 105 being identical with each other the feeding device and other mechanism for operating the feeding device of one of said sections A to E will suffice for an understanding of all.

The machine is designed to be actuated by a 110 motor 1, the shaft 2 of which is provided with a pinion 3 which cooperates with a gear 4 which in turn meshes with a pinion 5, the latter of which actuates a pinion 6. These lat- 115 ter pinions are respectively secured to shafts 7 and 8. The shaft 8 has a feed roller 9 se- 120 cured thereto and the shaft 12 is provided with the roller 10 which is driven by a pinion 11 mounted on the shaft 12, the pinion and 125 shaft being driven by a pinion 13 secured to 130 said shaft 8. The shaft 14 upon which the gear 4 is mounted carries another gear 15 which meshes with the gear 16 provided upon 135 the shaft 19. The shaft 17 is provided with 140 another gear 20 which cooperates with gear 145 21, the latter being secured to the shaft 22, 150 all of which is clearly shown in Fig. 2. The 155 actuation of the gear 18 transmits motion to 160 the rod 23 which is connected to a lever 24, 165 one end of which is secured to the shaft 25. 170 This shaft has an arm 26 extending therefrom 175 and a link 27 is connected to the end of the arm 180 26 and has its opposite end 28 secured to a re- 185 ciprocable carriage 29, clearly shown in Figs. 190 5, 6 and 7. The carriage 29 slides in a sup- 195 port 30 which in turn supports a stack of 200 newspaper sections or sheets 31, which sec- 205 tions or sheets are intermittently fed to 210 105 110 115 120 125 130 wards the carriage through the medium of the feeding mechanism 32, which in the present instance consists of a number of belts 33 traveling around pulleys designated 34 and 35. The means for causing an intermittent actuation of this feeding mechanism is clearly shown in Figs. 9 and 10, and includes an arm 36 secured to the shaft 25. A link 37 the opposite ends of which are respectively secured to the arm 36 and to the arm 38, transmits the rocking motion of the shaft 25 to the arm 38. The arm 38 is provided with a pawl 39 which cooperates with a ratchet 40 which it is evident will cause the belts 33 to be intermittently actuated upon each oscillation of the shaft 25, and will therefore feed the paper sections 31 toward the support 30. The newspaper sections or sheets 31 rest upon abutments 41 which are secured to a bar 42 which supports said abutments.

The support 30 is provided with a plurality of parallel grooves 32 and 44 which respectively receive extensions 45 and 46 of the reciprocable carriage 29. It is understood that each paper feeding device such as A to E, is provided with a plurality of these carriages, 29, as clearly shown in Fig. 3, and in view of the fact that each carriage is identical with the other, an explanation of one will suffice for an understanding of all. The structure of these carriages and the means provided thereon for feeding a sheet or section from one of the several stacks is clearly shown in Figs. 5, 6 and 7, and includes a plurality of spring pressed dogs, each of which is provided with needles which are designed to prick into the lowermost sheet or newspaper section to cause said sheet or section to be moved away from the abutment 41 and then moved in the opposite direction towards the rollers 9 and 10, and thence to other mechanism from which it is moved to the next device such as B. The dogs whereby the sheet or newspaper section is initially moved from the abutment 41 are designated 47 and are disposed on opposite sides of a centrally arranged rib 48 which is a part of the reciprocable carriage 29. These dogs are pivotally secured to a shaft 49 which extends transversely through the centrally arranged rib 48 and are provided with anti-friction rollers 50, and are maintained in a position to engage the lowermost sheet or section by means of the expansion spring 51 which normally tends to move one end of these dogs towards said section. It is evident that when the carriage is moved in the direction of the arrow illustrated in Fig. 5, that the needles 52 of the dogs 47 will engage the lowermost sheet or section and move it in the direction of the arrow and cause it to be released from the abutment 41. Upon the movement of the carriage 29 in the direction of the arrow illustrated in Fig. 6 the dogs designated 53—53 will engage the lowermost sheet or newspaper section and move said

section toward the feed rollers 9 and 10. These last mentioned dogs 53—53 are actuated towards the newspaper sections or sheet by springs 54 and are also pivotally connected to the centrally arranged rib 48 of said carriage.

In order to cause the dogs 47 to release the sheet prior to the introduction of the sheet between the rolls 9 and 10, the carriage support 30 is provided with cam tracks 55—55, the cam face 56 thereof being designed to engage the roller 50 of said dog 47 and cause the end of the dog carrying the needles to be moved downwardly and out of engagement with the newspaper sheet or section. To permit of this the carriage 29 is recessed as at 57 which will allow the roller to be moved sufficiently to permit the needle to be retracted from the sheet when the roller is engaged by the cam face 56, in which position it will remain during the forward movement of the carriage in the cam track 55. Each of the dogs 47 and 53 includes a body generally designated 58. A removable block 59 and the needles which are interposed between a portion of the body 58 and the removable block 59 are held in associated relation by a screw 60 which enters the body 58. The end of the body 58 and the corresponding end of block or bar 59 are correspondingly inclined to give needles 52 an inclination to facilitate grasping the paper sections, as shown in Fig. 5. Springs 59^a, shown in dotted lines in Figs. 5 and 6 tend to force members 59 from body 58. This structure is clearly shown in Fig. 8, from an inspection of which it is evident that upon the removal of the screw 60 the needles carried by said dogs may be changed or adjusted, depending upon any contingency which may arise.

In Fig. 11 a means is shown whereby the position of the carriage carrying the dogs may be varied with relation to other portions of the structure. This means includes the arm 26 and an element 61 arranged upon the shaft 25. This element 61 is provided with upwardly and laterally extending lugs 62 which are arranged upon opposite sides of a block 63 provided upon the arm 26. These lugs 62 respectively carry adjusting screws 64 and 65 which when actuated will, through the medium of the movement of the arm 26, and the link 27, cause an adjustment of the carriage 29 which carries said dogs and thereby permit the carriage to be arranged in various positions relatively to other elements of the structure such as the rollers 9 and 10.

From the foregoing description it is evident that a simple and effective structure is provided whereby a sheet or newspaper section may be engaged and moved from an abutment or support and then moved from said position to another position at which latter position the newspaper sheet or section may be fed to other instrumentalities of the

device. It is further manifest that a means is provided whereby the dogs which cause the initial movement of the sheet or section are caused to be released from the newspaper sheet or section so that it may be moved with respect to said dogs prior to the movement of the sheet towards said other instrumentalities of the machine, and will not cause any injury to occur to the sheet during these operations.

10 Having thus described my invention what I claim is:

1. In a machine of the class specified, the combination of a stack for holding paper sections and feeding mechanism for the same comprising sliding members carrying needles adapted to engage the lowermost paper section in the stack, said members being made with a detachable bar between which the needles may be detachably secured, said detachable bar having a slanting surface and the member carrying it having a correspond-

ingly slanting surface, between which surfaces the needles may be detachably held.

2. Needle holding devices comprising separable members with needles interposed between them and means for drawing said members together, the cooperating ends of the separable members between which the needles are interposed being inclined to the means for drawing said members together, whereby said drawing means will exert a wedge-like or clamping action on the needles.

3. Needle holding devices comprising separable members with needles interposed between them and means for drawing said members together, a spring tending to separate said members.

In witness whereof, I hereunto subscribe my name this 16th day of October A. D., 1926.

SEVERIN HALVORSEN.
